Primary Examiner — Philip S Hyder(74) *Attorney, Agent, or Firm* — FisherBroyles, LLP;
Craig W. Mueller**CLAIM**

The ornamental design for a knife, as shown and described.

DESCRIPTION

FIG. 1 is a perspective view of the knife;
FIG. 2 is a front elevation view thereof;
FIG. 3 is a rear elevation view thereof;
FIG. 4 is a right elevation view thereof;
FIG. 5 is a left elevation view thereof;
FIG. 6 is a top plan view thereof;
FIG. 7 is a bottom plan view thereof;
FIG. 8 is a perspective view of another embodiment of the knife;
FIG. 9 is a front elevation view thereof;
FIG. 10 is a rear elevation view thereof;
FIG. 11 is a right elevation view thereof;
FIG. 12 is a left elevation view thereof;
FIG. 13 is a top plan view thereof; and,
FIG. 14 is a bottom plan view thereof.
The broken lines depict portions of the knife that are not considered part of the claimed design.
